CLAIM

The ornamental design for a sport mannequin, as shown and described.

DESCRIPTION

FIG. 1 is a perspective view of a sport mannequin showing the design of the present invention

FIG. 2 is a front elevational view thereof;

FIG. 3 is a rear elevational view thereof

FIG. 4 is a left side elevational view thereof, the right elevational view being a mirror image thereof;

FIG. 5 is a top plan view thereof;

FIG. 6 is a bottom plan view thereof;

FIG. 7 is a perspective view of a second embodiment of a sport mannequin, the only difference being the orientation of the arms; and,

FIG. 8 is a perspective view of a third embodiment of a sport mannequin, the only difference being the orientation of the arms.
